GESELLSCHAFT, OF ESSEN-ON-THE-RUHR, GERMANY

PRINTING MECHANISM FOR CASH REGISTERS

Application filed September 28, 1929, Serial No. 395,914, and in Germany October 8, 1928.

The present invention relates to printing mechanism for cash registers and similar machines, and more particularly to mechanism of that kind for printing the set of calculated amount several times in succession.

According to the invention an arrangement is provided which has a manually operated special drive for the platen, besides the driving means operated by the machine drive, this special driving means providing the possibility of printing the amount for which the type carriers are set, independent of the machine drive.

15 The appended drawing shows an embodiment of the invention.

Fig. 1 being a side view of the special driving and locking means of the device, and

20 Fig. 2 being a side view of the special drive and of the platen arrangement.

Referring now to Fig. 2, a platen 1 is guided by means of pins 2 in fixed slots 3 and hinged by bolt 4 to a frame 5, 5', 30, journaled upon a fixed shaft 6, and positively connected by means of a compression spring 14 with a lever 8' also journaled upon shaft 6. Lever 8' has an attachment 8 with a face 7, and frame 5, 5', 30 has an arm 10, face 7 abutting with arm 10. Lever 8' cooperates over roller 12 and under the influence of spring 11 fastened to attachment 8, with a cam disk 13 fast on driving shaft 31. Lever 8' furthermore engages by means of pin 23 a slot 22 of a thrust bar 25 hinged to a locking lever 18 which is journaled on a fixed bar 32, said locking lever abutting with its free end upon a notch 29 of a shaft 20 and normally preventing by means of a shoulder 17, the platen 1 from moving relatively to the set of type wheels 24. When driving shaft 31 makes one revolution in a counter-clockwise direction during the operation of the machine, lever 8' is lifted three times by cams 15 of cam disk 13 whereby every time spring 14 is compressed and subsequently locking lever 18 is lifted by pin 23 coming into contact with the upper end of slot 22. Platen 1 is thereby released, performs the printing operation under the influence of spring 14 which is compressed

by the lifted arm 8 and is then again brought back into the locked position by spring 11. Slot 22 permits the printing motion of the platen. This arrangement permits the printing of three impressions during one operation of the machine, by means of the machine drive which actuates shaft 31.

The special driving means mentioned above consists in a hand lever 33 journaled upon shaft 6, said lever being normally kept in contact with stop 34 of the machine frame, due to its own weight. Hand lever 33 is rigidly connected with an arm 36 by means of a sleeve 35, said arm extending under an arm 37 attached to lever 8', lever 8' being therefore not prevented from being rocked by cam disk 13. If hand lever 33 is moved to the right, it will carry along lever 8' by means of arm 36 and disengage platen 1 in the same manner in which this function is performed by means of one of the cams 15. In this manner the printing operation can be repeated any desirable number of times after the completion of the normal operation of the machine which actuates shaft 31 and cams 15.

Referring now to Fig. 1, the complete rocking of the hand lever is secured by means of a stroke-completion lock of well known design, which consists of ratchet segment 39 arranged on an arm 38 and a catch 42 secured in a medium position by spring 41.

In order to lock hand lever 33 during the normal operation of the machine, it is equipped with a locking pin 43 (See Fig. 1) which cooperates with the hook-shaped extension 44 of a slide 47 moving upon a shaft 31 of the driving mechanism of the machine, having a fixed stud 45, and being under the influence of a spring 46. Hook 44 normally engages pin 43 and thereby locks hand lever 33 in its position of rest. At the end of an operation of the machine, however, cam 48 of a disk 49 fast on shaft 31 comes into contact with a roller 51 of slide 47 and moves the latter towards the left, contrary to the action of spring 46, thereby releasing hand lever 33. Slide 47

is kept in its releasing position by a catch 52 which under the influence of spring 53, arrests a face 54 of slide 47 thereby preventing it from being pulled back by spring 46. At the end of the forward motion of hand lever 33, in a clockwise direction, a laterally extending pin 55 of the lever depresses the free end of catch 52 and moves the other end out of its locking contact with 10 54, so that slide 47 moves back into its initial position and engages locking pin 43 if hand lever 33 returns, thereby again locking the hand lever in its initial position. This results in the fact that the described locking 15 means on the one hand locks hand lever 33 against performance of the repeated printing operation, prior to, and during one normal operation of the machine and prevents on the other hand that more than one repeating impression is made subsequent to one normal operation of the machine. This however does not prevent the performance of a new operation of the machine, prior to a repeating impression.

25 In order to protect the repeating printing with the hand lever, subsequent to an operation of the machine, a locking means is provided for the releasing device of the machine. This locking means becomes operative with the normal operation of the machine and can only be made inoperative by operating hand lever 33.

The release of the machine drive is accomplished in conventional manner by depressing one of several release keys 56 (Fig. 1), whereby a locking segment 57 is rocked upwardly, and a releasing lever 61 is disengaged, said releasing lever being under the influence of a spring 59, thereby releasing a locking arm 62 of the main drive 35 shaft 63. At the end of the operation of the machine releasing lever 61 is returned 40 into its initial position and key 56 which has so far been retained in depressed position, is disengaged, so that it can return into 45 its position of rest, under the influence of its spring.

The release keys 56 cooperate furthermore with a key slide 65 having inclined faces 50 64, said key slide being imparted an upward motion by means of the respective key pin 66 if a release key is depressed. The motion of 65 is transmitted to a locking arm 74 journaled upon shaft 32, over bell crank 67, 55 68, rod 69 and bell crank 71, 72, said locking arm 74 being also under the influence of a spring 73 tending to rotate it counter-clockwise. If slide 65 is moved upward by pin 66 of key 56, the free end 75 of locking arm 74 is moved toward trap 70 pivoted on shaft 20 and influenced by spring 76, so that 75 becomes engaged by catch 77 of trap 70 and is so prevented from turning back again. Trap 70 is prevented from 60 moving in this position by a pin 80 mounted

on the machine frame. In this manner the levers connected with locking arm 74, including the key slide 56 are retained in the position imparted to them by depressing key 56.

Angular pieces 79 are journaled upon key bar 65 by means of studs 78, said pieces abutting with their arms 82, under the influence of springs 81, with the adjacent studs 78, locking faces 83 being in this position in the path of key pins 66, provided that key bar 65 is in its lifted position. After a release key 56 has been depressed, the other release keys are therefore locked by locking faces 83, the depressed key however is released at the end of the normal operation of the machine and passes during its return motion with its pin 66 over the corresponding inclined face of piece 83 so that it is also locked by face 83, after the completion of the normal operation of the machine. Therefore, a new normal operation of the machine cannot be accomplished as long as the key bar 65 is not returned from its lifted position.

90 In order to return key bar 65, trap 70 is provided with a cam 84 which extends into the path of a cam 85 of hand lever 33. As soon as lever 33 is moved, after the completion of a normal operation of the machine, to the right, in order to obtain a repeated impression, cam 85 and cam 84 turn the trap 70 so far in a counter-clockwise direction, that face 77 releases locking arm 74, said locking arm returning into its initial position together with parts 67, 68, 69, 71 and 72 and key slide 65, under the influence of spring 73. Only after the completion of the repeating impression, this completion being enforced due to the presence of locks 39 and 42, is it possible to perform a 95 subsequent new operation of the machine.

Having thus described my invention, I claim:

1. In a printing device for cash registers and calculating machines, type carriers, a platen for printing from said type carriers, means for actuating said platen from the drive of the machine during normal operation of the machine, manually operated special means for printing from said type carriers by actuating said platen independent of said drive, and a means for locking said special means during the normal operation of the machine.

110 2. In a printing device for cash registers and calculating machines, type carriers, a platen for printing from said type carriers, means for actuating said platen from the drive of the machine during normal operation of the machine, manually operated special means for printing from said type carriers by actuating said platen independent of said drive, and a means for locking said special means during the normal operation 115 120 125 130

of the machine and for releasing it again at the end of the normal operation.

3. In a printing device for cash registers and calculating machines, type carriers, a platen for printing from said type carriers, means for actuating said platen from the drive of the machine during normal operation of the machine, manually operated special means for printing from said type carriers by actuating said platen independent of said drive, a means for locking said special means during the normal operation of the machine and for releasing it again at the end of the normal operation, for a subsequent repeating printing operation, and means for automatically locking it again at the end of the printing operation, in order to allow only one operation of said special means subsequent to a normal operation.

4. In a printing device for cash registers and calculating machines, type carriers, a platen for printing from said type carriers, means for actuating said platen from the drive of the machine during normal operation, a cam disk actuated by said machine drive, a manually operated special means having a locking pin and a laterally extending pin for printing from said type carriers by actuating said platen independently of said normal drive, a slide having a hook-shaped extension, a catch cooperating with said slide and with said laterally-extending pin, said hook-shaped extension normally locking said special means by engaging said locking pin, said cam disk moving said extension from its locking position at the end of the normal operation of the machine thereby releasing said locking pin, said catch retaining said slide in its locking position until said special means is operated and said laterally-extending pin, actuating said catch, releases said slide, and the hook-shaped extension of said slide re-engaging said locking pin of said special means, upon the return of said special means into its initial position.

5. In a printing device for cash registers and calculating machines, type carriers, a platen for printing from said type carriers, means for actuating said platen from the drive of the machine during the normal operation, a manually operated special means for printing from said type carriers by actuating said platen independent of said normal drive, manually controlled means for initiating the operation of said normal actuating means, locking means cooperating with said manually controlled means, said locking means preventing a subsequent normal operation until a repeating printing operation has been performed with said special means.

6. In a printing device for cash registers and calculating machines, type carriers, a

platen for printing from said type carriers, means for actuating said platen from the drive of said machine during the normal operation, a manually operated special means having a cam for printing from said type carriers by actuating said platen independent of said normal drive, means for initiating operation of said normal actuating means, a locking arm positively connected with said initiating means, a trap engaging said locking arm if said initiating means are actuated, said trap being released by said cam if said special means is actuated.

7. In a printing device for cash registers and calculating machines, type carriers, a platen for printing from said type carriers, means for actuating said platen from the drive of said machine during the normal operation, a manually operated special means for printing from said type carriers by actuating said platen independent of said normal drive, manually controlled means for initiating the operation of said normal actuating means, locking means cooperating with said manually controlled means, said locking means preventing a subsequent normal operation until a repeating printing operation has been performed with said special means, a slide actuated together with said manually controlled means and locking said manually-controlled means in the operative position, and means for locking said slide in its operative position, thereby preventing a subsequent operation of said manually controlled means until a repeating printing operation is performed with said special means.

8. In a printing device for cash registers and calculating machines, type carriers, a platen for printing from said type carriers, means for actuating said platen from the drive of the machine during normal operation of the machine, a manually operated special means for printing from said type carriers by actuating said platen independent of said drive, release keys having laterally extending pins, for initiating operation of said normal drive, a key slide having inclined faces cooperating with said pins and being actuated by said pins if a key is depressed, means for locking said key slide in its actuated position until a repeating printing operation is performed with said special means, angular pieces rotatably connected to said key slide, said angular pieces locking the inoperative release keys if said key slide is actuated, and locking the actuated key after its release, said key slide arresting in its locked position all the release keys in their normal position at the end of the normal operation of the machine.

9. In a printing device for cash registers and calculating machines, type carriers, a platen for printing from said type carriers, means for actuating said platen from the

drive of the machine during normal operation of the machine, manually operated special means for printing from said type carriers by actuating said platen independent of said drive, a second actuating means for said platen, said second means being actuated by said special means, and comprising a spring prepared for action, and subsequently released by the operation of said special means, thereby actuating the platen, and a stroke-completion lock securing complete actuation of said special means.

The foregoing specification signed this 13th day of September, 1929.

AUGUST RADERMACHER.
